MOBILE SHOP

Kibbey W. Couse, Newark, N. J.

Original application May 10, 1956, D. 41,429, now
D. 180,893, dated September 3, 1957. Divided and this application April 16, 1957, Serial No. 45,762

Term of patent 14 years

(Cl. D14—3)

Figure 1 is a perspective view of a mobile shop embodying my new design. The broken line portions of a vehicle are shown for purposes of illustration only; and

This application is a division of my co-pending United States application Serial Number D. 41,429, filed May 10, 1956, and entitled Mobile Machine Shop; which application has now matured into Design Patent D. 180,893, issued September 3, 1957.

I claim:

The ornamental design for a mobile shop, as shown and described.
